BEDSTEAD END FRAME

Robert M. Kupchick, Chicago, Ill., assignor to Dresher
Manufacturing Company, Chicago, Ill., a corporation
of Illinois

Filed Feb. 17, 1964, Ser. No. 78,649

Term of patent 14 years

(Cl. D5—2)

FIG. 1 is a front elevational view of a bedstead end frame embodying my new design;

FIG. 2 is an end elevation view of the same;

FIG. 3 is a top plan view of the same; and

FIG. 4 is a bottom plan view of the same.

The side and end of the Bedstead End Frame not shown are substantially the same as the side and end shown.

I claim:

The ornamental design for a bedstead end frame, substantially as shown and described.
